BENTON C. ROWELL, DECEASED.

MECHANISM FOR OPERATING BRAKES IN SIGNAL SYSTEMS.

1,193,472.

Specification of Letters Patent. Patented Aug. 1, 1916.

Application filed February 13, 1911. Serial No. 608,246.

To all whom it may concern:

Be it known that I, BENTON C. ROWELL, a citizen of the United States, residing in Chicago, in the county of Cook and State 5 of Illinois, have invented a new and useful Improvement in Mechanism for Operating Brakes in Signal Systems, of which the following is a specification.

This invention relates to signal controlled 10 train brake setting mechanism, and is adapted for use on either single tracks having trains passing thereover in either direction, or on double tracks in which the trains pass in one direction only on each track. 15 The objects of the invention are: First, to provide mechanism which will set the train brakes when the visual signals are at danger and the engineer of the train runs by the same without stopping; second, to 20 provide mechanism which will set the train brakes when the visual signals fail to properly go to danger when the train passes; third, to provide mechanism which will set the train brakes when the home signal is 25 clear but the distant signal indicates caution and the engineer fails to reduce speed to a predetermined limit.

The invention further consists in the improvements in the parts and devices and in 30 the novel combinations of parts and devices herein shown, described or claimed.

Briefly, the entire mechanism comprises in co-operative combination, a track instrument train or trip which is disposed along 35 side the track and is adapted to assume either a safety position or a danger position, and in the latter case will set or trip suitable mechanism on the locomotive of a train as the latter passes over the track instrument to set the train brakes; mechanism 40 for setting or controlling the track instrument, the same being controlled by electrical circuits and operated from the visual signals with which it is mechanically connected.

In the drawings forming a part of this specification, Figure 1 is a plan view showing the mechanism for operating the track instrument with parts removed. Fig. 2 is 45 a longitudinal, vertical section of the structure shown in Fig. 1. Figs. 3 and 4 are detail views showing various parts of my improved mechanism. Fig. 5 is a diagrammatic view showing the controlling electrical circuits for the train stop shifting

mechanism as arranged for a single track railway over which the trains run in both directions, the west bound signal arms being both shown at clear to indicate the positions they would be in when a west bound 60 train is in the section *a* of track and the east bound signal arms being at danger to indicate their normal position. Fig. 6 is a view similar to that of Fig. 5 showing the arrangement as used in connection with a 65 west bound track of a double track railway, the signal arms being shown at clear to indicate the position assumed thereby when a west bound train is on the sub-section of track to the east of that referenced *a*. 70 Figs. 7 and 8 are side and front elevations, respectively, of one form of signal adapted for use with my improvements, and Fig. 9 is a detail side elevation of part of the shifting appliance and more particularly those 75 parts shown in Figs. 3 and 4 of the drawing. Fig. 10 is a partial sectional view showing the operating mechanism on the shaft 2 for two signal posts, one for trains going in each direction.

Referring more particularly to Figs. 1 and 2, 1 represents an inclosed casing in which is located the mechanism for operating the track instrument or brake setting device E, it being understood that this mechanism is mechanically operated from the motive power, which is used for moving the signal arms of the signal H and is electrically controlled as hereinafter described. The signals H used may be of any suitable 90 or well known type, having arms indicating safety, caution and danger, and it is immaterial to my invention how the signal circuits are arranged for controlling the movements of the arms, so long as the arms are arranged and operated to indicate the three positions stated. And it is further immaterial whether or not two arms are used, one a home and the other a distant signal, or whether a single arm is used to 95 indicate the three positions, but for clearness of illustration, I have shown in Figs. 5 and 6, signals which employ two arms for each direction of movement of the train. The signal arms are shifted by any suitable 100 motive power (not shown) controlled by the signal circuits, and this shifting mechanism includes a rock shaft 2 (Figs. 7 and 8) which is extended into the casing 1, and to which is keyed a lever 3, having formed 105 110

thereon ends 103 passing around each side of a slidable shaft 4 mounted in bearings 5 in the casing 1. Secured to the shaft 4 is a collar 6, and slidably mounted thereon is a sleeve 7, the latter being limited in its movements on the shaft 4 away from the collar 6 by a shoulder 8 formed on the shaft 4.

A coil spring 9 is placed on the shaft 4 between the collar 6 and sleeve 7, whereby the sleeve 7 may be moved toward the collar 6 by the forked lever 3 against the compression of the spring 9 and independently of any movement of the shaft 4. A cross shaft 11 is mounted in the casing 1 and to this shaft are keyed a pair of lever arms 10 and a sprocket gear 12. The arms 10 are connected at their upper ends by a cross pin 13 which engages in a slot 13^a formed in shaft 4. A sprocket chain 16 engages the gear 12 and is guided by idler rollers 116, and to the ends of the chain 16 are secured wires 117 which pass through packed/or stuffed holes in the casing to prevent leaking of the oil or other non-freezing liquid with which the case is preferably filled. The wires 117 lead to the track instrument or brake setting device E (see Figs. 5 and 6) and operate the same to and from the position where it will trip the brake setting valve on the locomotive. This track instrument or brake setting device E is preferably of the type shown and described in my pending application No. 574,440 and is provided with a counterweight which will automatically throw the track instrument into the danger position to trip the brake setting valve of the locomotive, unless otherwise prevented by the position of the mechanism hereinafter described. The track instrument E is shown in Figs. 5 and 6, as in the danger position, and the location and arrangement of the devices as shown in Fig. 2 correspond to the danger position of the track instrument E.

From the foregoing description, it will be seen that the movements and position of the brake setting device E are governed by the movements of the shaft 4, that is, through means of the slot 13^a, pin 13, arms 10, 10, shaft 11, gear 12, chain 16 and wires 117. In order to prevent too sudden movements of the shaft 4 within the case 1 in either direction under the impulse of the spring 9, I provide each end of the shaft 4 with an interchangeable piston 14, each of said pistons operating in a cylinder 15, and I fill the casing to a level above the shaft 4 with oil or other non-freezing liquid, and by varying the clearance 36 between the pistons 14 and cylinders 15, it will be seen that the speed of movement of the shaft 4 can be regulated as desired, since the rate of displacement of the liquid from either side of the piston to the other will be governed

by the clearance 36. The casing, as shown, is preferably provided with a removable cover 34, the latter having detachably secured thereto a magnet chamber 35.

For controlling the movements of the shaft 4, I provide two oppositely arranged levers 17 and 25, pivoted respectively at 18 and 26, and provided with oppositely arranged shoulders 19 and 27, the shoulder 19 being adapted to engage the collar 6 to prevent the latter from moving toward the right, as viewed in Fig. 2, and the shoulder 27 being adapted to engage the sleeve 7 to prevent the latter from moving to the left. The lever 17 with its shoulder 19 is normally held depressed by means of a link 20, pivotally connected to the lever 17, the link 20 being pivotally connected to a second lever 21, mounted on a pivot 23, the latter having a spring 22 therearound for normally urging the free end of the lever 21 upwardly, the lever 21 serving as an armature for the magnet 24, which, as will be hereinafter described, is normally kept energized. The lever 25 has pivoted thereto a link 28, to which is pivoted a lever 29, mounted on a pivot pin 31, the latter having a coiled spring 30 therearound, and the lever 29 serving as an armature for a magnet 32. The springs 22 and 30 are of such strength that they balance the weight of the levers 17 and 25, links 20 and 28 and armatures 21 and 29, respectively, and just tend to keep the inner ends of the armatures 21 and 29 raised, but as will be apparent, the energy stored up in the spring 9 when the latter is compressed between the collar 6 and sleeve 7 will be sufficient to counteract either of the springs 22 or 30, and force the inner ends of the armatures 21 and 29 downwardly at any time when the magnets 24 and 32 are not energized. As will be hereinafter described, the magnet 32 is normally deenergized, and hence the shoulder 27 will therefore be out of the path of movement of the sleeve 7. As has just been stated, when no trains are on the track, the magnet 24 is normally energized and the magnet 32 deenergized, and the shaft 4 therefore prevented from movement toward the right, as viewed in Fig. 2, that is, the brake setting device E is prevented from assuming a safety position.

I will now describe the electrical circuits which control the energizing and deenergizing of the magnets 24 and 32, and particular reference will be made to Fig. 5 to describe the arrangement for a single track adapted to have trains run thereover in both directions.

The track as shown is divided into a plurality of insulated sections *a*, *b*, *c* and *d*, each provided with a relay *a*¹, *b*¹, *c*¹ and *d*¹, and a track battery F connected in the usual manner.

H represents the signal post, provided with signal arms H¹ and H² representing the home and distant signals for west bound trains, respectively, and the home and distant signal arms H³ and H⁴, respectively, for east bound trains, the position of the west bound signal arms H¹ and H², as shown in Fig. 5, indicating clear, as the same would be when the train is on the subsection of track 5 a and the signal arms H³ and H⁴ being at danger, which is their normal position. The train stop E as shown in Fig. 5, is set at danger, the normal position of the same. At each signal station H, where my improvements are to be used, there is provided a main battery C and signal relays A and B, the latter, as will be understood, being normally energized. The circuit for the magnet A is made through the wire 90 having a battery 90' therein, through magnet A, wire 90, e, e of relay d¹, h, h of relay c¹, through circuit breaker 53 on the brake setting device E, which circuit breaker is closed when the device E is at danger, through k, k of relay 10 b¹, wire 48 and wire 90. The circuit for the relay B is formed through the wire 80, relay B, wire 80, m, m of relay a¹, l, l of relay b¹, through circuit breaker 54, closed when the device E is at danger, from circuit breaker 25 54 through i, i of relay c¹ and back through wire 80 having battery 80' therein to relay B. Inasmuch as the relays A and B are normally energized, it will be apparent that the contacts between the points 36 and 37, 30 and 38 and 39 will be closed, and that therefore the magnet 24 will be normally energized by current from the battery C through the following circuit. From battery C through wire 34, magnet 24, wire 40, which 35 leads to the contacts 37 and 39, through 37 and 36 and 39 and 38 to wire 35, and by the latter back again to the opposite side of battery C. The magnet 32 will be normally de-energized, since the circuit for the same from 40 the battery C which includes the wire 50 will be broken at the points g, g of relay c¹, or at j, j of relay b¹, since the latter points g, g and j, j are back points of the respective relays c¹ and b¹. 45

The circuit breakers 42, 142, and 47 and 50 147 are normally open, that is, are open when the home signal arms H¹ and H³ are at danger, and the circuit breakers 44 and 49 are closed when the distant signal arms H² and H⁴ indicate caution. As a train comes from the east, the operation is as follows: Upon the train entering the track section a, the relay a¹ will be de-energized, and consequently the circuit for the relay B will be 55 broken at m, m, which, in turn will open the contacts 36, 37. The circuit of relay B will be kept open as the train continues along the section b by the opening of the points l, l of relay b¹, and this circuit will again be broken 60 when the train enters the section c of the 65

track by the opening of the points i, i of relay c¹, and hence it will be seen that the magnet 24 can not be energized by any circuits which include the contacts 36, 37 while a train is passing along the track through the sections a, b and c. 70

It will be understood that before the train enters the section b, the home signal H¹ for the west bound train will have been cleared by the proper signal circuits for controlling the same, and hence the circuit breakers 47 and 147 will be closed. The signal arm H¹, in clearing, will of course rock the shaft 2, and the latter, through the medium of the lever 3, will move the sleeve 7 toward the right, as shown in Fig. 2, but inasmuch as the shoulder 19 of the lever 17 is normally held down, and magnet 24 is still energized, the spring 9 will be compressed and the shaft 4 will not be moved. 75

When the train enters the section b, the relay b¹ will be de-energized, which will open the contacts l, l and k, k and will close the back points j, j. The opening of the contacts k, k will then break the circuit for the relay A, and hence open the contacts 38 and 39, but in order to keep the magnet 24 energized, an auxiliary circuit is provided as follows: Wire 41 taps off of wire 40 and through wire 46 passes through circuit breaker 47, now closed, wire 46, wire 35 through battery C and back through wire 34, to the magnet 24. Also as soon as the train enters the track section b, the magnet 32 will be energized due to the circuit for the same being closed by the back points j, j of relay b¹ and upon the magnet 32 being energized, it will be apparent that the shoulder 27 of the lever 25 (see Fig. 2) will be dropped down in front of the sleeve 7, 80 which, as previously described, was moved to the right by the lever 3 when the signal arm H¹ went to the clear position. The signal arm H¹ will go to danger when the circuit for relay A is broken at k, k and in so doing, will move the lever 3 through the intermediary of the shaft 2 to the position as shown in Fig. 2. But, in view of the fact that the shoulder 27 is now in the path of the sleeve 7, the latter will not move with the lever 3. The signal arm H¹ in returning to danger, will break or open the circuit breaker 47, which will allow the magnet 24 to become de-energized, whereupon the lever 17 with its shoulder 19, will be raised 85 out of the path of the collar 6, and the collar 6 with the shaft 4 will be projected to the right under the impulse of the spring 9, inasmuch as the sleeve 7 is held by the shoulder 27. The movement of the shaft 4 to the right will now set the brake setting device E in the safety position. As the train passes onto the section c, the circuit for the magnet 32 will still be kept closed, due to the closing of the back points g, g of relay 90

c^1 , and hence the shoulder 27 will be held in the path of the sleeve 7 to prevent the same from moving toward the left while the train is on the section c . After the train has 5 passed from the section of track c , the circuit for the magnet 32 will then be broken and the counterweight on the track instrument E will automatically throw the same to danger, which movement will move the 10 shaft 4 of the structure shown in Fig. 2 to the left or normal position, and the apparatus will be in the same condition as before the train entered the section a .

The foregoing sequence of operations and 15 formation of circuits takes place when the signal for the west-bound train indicates clear. If, however, the signal arm indicates caution, the following circuits are provided in order to compel the engineer to reduce speed to a predetermined limit in traveling over the section b of the track. When 20 the signal arm H^2 indicates caution, as has been previously described, the circuit breaker 49 will be closed, and hence a patch 25 circuit for the break in the circuit of the relay A which occurs at h , h when the relay b^1 is deenergized, will be formed as follows, in order to close the contacts 38, 39 and keep the magnet 24 energized. Wire 48 is 30 tapped to one side of the contacts h , h and leads to circuit breaker 49, circuit breaker 147, also closed, and back through wire 48 to the opposite side of the points h , h . The signal arms retain their caution indication 35 so long as the relay A is energized. This may be accomplished in a number of ways, one being by passing the circuits for controlling the signal arms themselves through front contacts 55' and 57' of the magnet A, 40 said circuit being indicated on the drawing by the wire 155 shown in Fig. 6. (This feature of wiring being shown in this figure because of the relative simplicity of the wiring in this figure over Fig. 5). Hence, so 45 long as the train is on the section b of the track while the signal arm H^2 indicates caution, the magnet 24 will be energized and the collar 6 on the shaft 4 will be prevented from movement. The circuit for the relay 50 A will therefore not be broken until the train reaches the section c of the track, which will open the contacts h , h of the relay c^1 , whereupon the relay A will become deenergized and in turn the magnet 24 55 will be deenergized. With this condition, therefore, the shaft 4 will not operate the track instrument E until the train reaches the section c , and inasmuch as it takes an appreciable amount of time for the shaft 60 4 to move, due to the displacement of the oil or other liquid in the cylinder 15 from one side of the pistons 14 to the other, it will be seen that the speed of the train must be reduced to a predetermined limit to allow 65 the operations to take place while the train

is passing from the section b of the track to the section c , and this speed may be varied as before described by varying the sizes of the interchangeable pistons 14.

The track instrument E is located directly opposite the insulation between the track sections b and c so that it will operate, the same upon trains going in both directions. In actual practice, the valve in the train pipe for setting the brakes and which 75 is adapted to be tripped by the track instrument is carried on the locomotive tender so that the engine on a west bound train, for instance, will pass into the section c before the track instrument can operate the valve 80 on the tender, but there is a sufficient interval of time between such entrance of the engine into the section c and the connection, between the track instrument and the valve on the tender, to allow the apparatus to 85 clear, provided the speed of the train has been reduced to the predetermined rate for which the apparatus has been set or adjusted.

The operation for trains eastbound is as 90 follows: As before, the relays A and B are normally energized, as is also the magnet 24, while the magnet 32 is demagnetized, the track instrument E is in the danger position, the signal arms for the eastbound train 95 H^3 and H^4 are also at danger and the mechanism, shown more particularly in Fig. 2, is in the position as there shown. As the train enters upon the section d , the circuit for the relay A will be broken at e , e and as the 100 train continues eastward over the sections c and b , the circuit for the relay A will be kept open when the relays c^1 and b^1 are in turn deenergized which causes the opening of the contacts h , h and h , h and hence the 105 magnet 24 cannot be energized by any circuit which passes through the contacts 38 and 39. As soon as the train enters the section c , the circuit for the relay B will be broken at the contacts i , i when relay c^1 is 110 deenergized, but the magnet 24 will be kept magnetized for the necessary length of time by the following auxiliary circuit. Starting from battery C through wire 34, magnet 24, wire 40, wire 41, circuit breaker 42 (which 115 is closed since the home signal H^3 has gone to clear), then through wire 41 to wire 35 back to the opposite side of battery C. As in the case of a westbound train, when the signal arm H^3 goes to clear, the sleeve 7 on 120 the shaft 4 will be moved to the right, and the collar 6 will be prevented from movement due to the shoulder 19 being held in the path of the same while the magnet 24 is energized. Upon the signal arm H^3 falling 125 to danger as the train continues over the section c , the lever 3 will be returned to the position shown in Fig 2, but the sleeve 7 will be prevented from following the movements of the arm 3, because the shoulder 27 on the 130

lever 25 will have been lowered due to the fact that the magnet 32 will have been energized immediately upon the train entering the section *c* through the following circuit. 5 From battery C through wire 34, magnet 32, wire 50 through back points *g*, *g* of relay *c*¹, wire 50 to wire 50, 51, wire 50, contacts *n*, *n* of relay *a*¹, wire 50 back to wire 35 and then to the opposite side of battery C. As soon 10 as the signal arm *H*³ returns to danger, the circuit for energizing the magnet 24 will be broken at the circuit breaker 42, and the shoulder 19 will then be withdrawn from engagement with the collar 6 on the shaft 4, 15 and the latter will then be projected to the right, as viewed in Fig. 2, and the track instrument or brake setting device E placed in the safety or inoperative position. Circuit for magnet 32 will still be kept closed 20 when the train enters upon the section *b* due to the closing of the back points *j*, *j* of relay *b*¹, but as soon as the train passes onto the section *a*, the magnet 32 will become demagnetized and the sleeve 7 on the shaft 4 25 will be free to move to the left, as viewed in Fig. 2 under the impulse of the counterweight on the track instrument or brake setting device E, whereupon the parts will assume the danger position, as shown in 30 Fig. 2.

The foregoing operations are such as occur when the signals indicate clear, but should the signal arms indicate caution, the following circuits will be brought into play 35 to compel the engineer to reduce speed in traversing the section *c* of the track. The circuit for the relay B will be broken, as before, at the contacts *i*, *i* of relay *c*¹, but inasmuch as the distant signal arm *H*⁴ will indicate caution, the circuit breaker 44 will be closed and the gap in the circuit at *i*, *i* will be bridged by the following circuit which starts at one side of *i*, *i* and then through wire 43, circuit breaker 44, circuit breaker 40 442, now closed, wire 43 back again to the opposite side of the contacts *i*, *i*. This circuit will keep the magnet 24 energized and prevent the movement of the collar 6 with the shaft 4 to the right, as viewed in Fig. 2, 45 until the train reaches the section *b* of the track, whereupon the circuit for energizing the relay B will be broken at the points *l*, *l* of relay *b*¹ when the latter becomes deenergized. As soon as the magnet 24 is thus 50 caused to be deenergized, the shoulder 19 will be lifted out of the path of the collar 6 and the shaft 4 then allowed to be moved to the right, as viewed in Fig. 2, under the impulse of the spring 9, but as will be obvious, the time required for this change of position of the shaft 4, and hence of the brake setting device E, is an appreciable amount and the change must take place while the train is 55 passing from the section *c* to the section *b*, and hence the speed of the train must be

reduced to the predetermined limit in order to allow the track instrument E to be moved to the safety or inoperative position in the same manner as described for a westbound train. 70

Referring now to the circuits for controlling the brake setting device as applied to a double track, and as more particularly shown in Fig. 6. The circuits shown in this connection for a track over which the trains 75 run in one direction only, comprise substantially one half of those shown and described for the single track shown in Fig. 5, and the formation of the circuits is similar to the formation of circuits for a westbound 80 train over the track shown in Fig. 5. In this system the signal H is shown as provided with two signal arms *H*⁵ and *H*⁶, a signal relay D, main battery C¹ and track instrument E¹, it being understood that the relay 85 D is normally energized as were the relays A and B in the previously described system, and the circuit through the relay D is formed as follows through wire 161 from a battery 161¹, relay D, wire 162 through contact *t*¹ of 90 relay A¹ through circuit breaker 65 (closed when the track instrument E¹ is at danger), through contact *s* of relay *b*¹, contact *r*¹ of relay *c*¹ and out of wire 161 to battery. The magnet 24 is normally energized while 95 the relay D is kept energized by a circuit which starts at battery C¹, through wire 34, magnet 24, wire 58, contacts 57, 55, wire 56, back to the opposite side of C¹. The circuit for the magnet 32 is normally broken at the 100 back point *t* of relay *a*¹. As the train enters section *a* the circuit for the relay D will be broken at *t*¹ and hence the contacts 55, 57 will be broken, but in order to keep the magnet 24 energized the necessary length of time, the 105 gap at 55, 57 is bridged by a circuit which includes the wire 59 which taps onto the wire 58 at the contact 57 and passes through the circuit breaker 60 (closed when the signal arm *H*⁵ is clear), then through wire 59 back 110 to wire 56, through battery C¹ and wire 34 back to the magnet 24. The signal arm *H*⁵ in going to clear will operate the lever 3 in a manner similar to that already described for the signal arms *H*¹ and *H*³, but the shaft 4 115 will be prevented from longitudinal movement, since the shoulder 19 will be held in the path of the collar 6, because the magnet 24 is still energized. The train, upon entering the section *a* of the track will cause the 120 magnet 32 to be energized, since the circuit for the same will be closed at back point *t* of the relay *a*¹, and hence the shoulder 27 will be moved into the path of the sleeve 7 which has previously been moved to the right by 125 the movement of the lever 3, and when the signal arm *H*⁵ drops back to danger, the sleeve 7 will be prevented from following the return movement of the lever 3 by the shoulder 27. As the signal arm *H*⁵ returns to dan- 130

ger, the circuit for energizing the magnet 24 will of course be broken at the circuit breaker 60, which will release the collar 6 and allow the shaft 4 to be moved to the right, as viewed in Fig. 2, under the impulse of the spring 9, which in turn will move the brake setting device E to the inoperative position. As the train continues its westward movement and enters upon the section of track b, the circuit for the magnet 32 is unaffected, but as soon as the train enters the section c of the track, the circuit for the magnet 32 is broken at the contact r of relay c^1 , and the shoulder 27 of the lever 25 will therefore be removed from the path of the sleeve 7 and the shaft 4 will be allowed to return to its normal position, that is, the one shown in Fig. 2, under the impulse of the counterweight of the track instrument E¹, which will of its own accord, return to the danger position.

The foregoing operations take place when the signal arm H⁵ indicates clear, but should the signal indicate caution, the circuit breaker at 62 will be closed and a patch circuit will be formed for keeping the relay D energized, as follows, to bridge the gap caused by the opening of the contact t^1 ; wire 61 taps onto wire 162, then through circuit breaker 62, wire 61, circuit breaker 160 (now closed), wire 61 back to the opposite side of the contact t^1 , and by means of this circuit the magnet 24 will be kept magnetized and the collar 6 thus prevented from movement until the train reaches the section b of the track where the circuit for the relay D will be broken at the contact s of relay b^1 .

From the foregoing description, it will be seen that the mechanism for operating the brake setting device will not be released until the train enters the section b, and inasmuch as an appreciable amount of time is required to allow the shaft 4 to move to the right, the engineer will be compelled to slow the speed of the train to give the mechanism time to operate while he is passing from the section a of the track to the section b.

I will now describe the mechanism for preventing the throwing of the track instrument to the safety position when the signal arm indicates clear, which might otherwise occur if any breaks were formed in the energizing circuits for the magnet 24 and particular reference will be made to the structure as shown in Figs. 2, 3 and 4. Formed integrally with the horizontal floor portion 33 of the case is a boss 67 in which is rotatably mounted a short shaft 66, the latter having secured thereto at the lower end a crank arm 68 to which is pivotally connected a link 72, the latter at its opposite end being pivotally connected to the lever 3 and operated thereby. Secured to the shaft 66 and mounted thereon above the boss 67 is a sleeve 69, the same being provided with a projec-

tion 169 which is adapted to cooperate with a corresponding projection 170 formed on the sleeve 70, the projection 169 and 170 forming what is commonly known as a knuckle joint. Mounted on the sleeves 70 and 69, and secured to each is a spring 71, the latter being adapted to move the two members 169 and 170 normally to engaging position, as shown in Fig. 3. The member 70 is provided at its upper end with a disk portion in which is provided a slot 74, the latter being located when the lever arm 3 is in the position shown in Fig. 2, under a lug or projection 121 formed on the outer end of the lever 21 and through which the projection 121 is adapted to pass should the magnet 24 become deenergized. The upper face of the disk 70 is provided with an inclined face 171, the latter forming at one end a shoulder 75. Under normal conditions, the lug 121 is disposed in a plane above the top of the shoulder 75 and should the magnet 24 become deenergized, the lug 121 will pass through the slot 74. When, however, the lever arm 3 is swung to the right, as viewed in Fig. 2, that is, when the signal arm goes to clear, the cam or inclined face 171 will engage under the projection 121 and will be rotated to a point where the shoulder 75 is beyond the projection 121, thus preventing the lever 21 from falling down, and thereby retaining the shoulder 19 in engagement with the collar 6 on the shaft 4. It will thus be seen that the track instrument E cannot be thrown to the safety position while the lever arm 3 is moved to the right, if for any reason the circuits for energizing the magnet 24 should become broken accidentally. If, while the signal arm is at clear, the energizing circuits for the magnet 24 become broken, the spring 9, which is under compression, will force the lug 121 down into engagement with the disk 70, and when the lever 3 is returned to the position shown in Fig. 2, the sleeve 70 will be prevented from returning with the sleeve 69, because the shoulder 75 will be engaged by the lug 121, and hence the collar 6 will not be released. As soon, however, as the magnet 24 becomes energized again, the lever arm 21 will be raised and the lug 121 removed from the path of the shoulder 75, whereupon the sleeve 70 will be returned by the spring 71 to the position shown in Fig. 3, which in turn will locate the recess or slot 74 beneath the lug 121, and the latter can then fall down as soon as the magnet 24 is deenergized to thereby release the collar 6 and allow the track instrument to assume the safety position. In the drawings, the slot 74 is shown as extended entirely through the disk 70, but in actual practice, the member 70 is made so that the slot extends down to near the bottom of the same and the lug 121 in its lowered position never leaves the slot.

In Figs. 7 and 8 is shown a signal of common form and the method of connecting this signal arm to the shaft 2 of my mechanism for operating the track instrument or brake setting device. The structure shown in Figs. 7 and 8 is for a signal having only a single arm which indicates the three positions, danger, caution and safety, but as previously pointed out in the specification, it is 10 immaterial to my invention whether a single arm signal is used or one having two arms, one for home signals and the other for distant signals, the only essential being that the first movement of the signal arm 15 must operate the shaft 2, and that further movements of the signal arm must retain the shaft in the position to which it is first moved until the signal arm returns to its normal position. In the device shown in 20 Figs. 7 and 8, 76 denotes the operating rod of the signal on which is fixed the pin 78, the latter being adapted to operate an escapement crank 77 keyed to the shaft 2. The dotted lines A, B and C show the three 25 positions of the operating rod 76. The first upward movement of the rod when the pin 78 has reached the level B, has operated during the early part of this upward movement the crank 77 and the shaft 2, and a 30 further upward movement of the pin 78 to the line C on the flat face 79 does not effect the rotation of the shaft 2, and as will be obvious, it is necessary for the pin 78 to travel back to the level A before the crank 35 77 and the shaft 2 are returned to their normal position. The effect of the movement of the pin 78 upon the operating mechanism occurs in the first small fractional part of the pin movement. Because of this fact 40 any accompanying movement given to the signals for a train moving in the opposite direction will be so slight as to not materially affect the position of these other signals. In other words, such movement is in- 45 sufficient to move said signals out of boundary position, although they may be slightly moved from their normal arrangement. Some of the movement is taken up in the back latch or loose connection of the parts, 50 and such as is not is without appreciable effect upon the signal indication.

As will be understood, the arrangement shown in Figs. 7 and 8 is merely illustrative of one form that can be employed with my 55 improvements and is such as would be used for operating a train stop adjacent one track of a double track railway. With a single track where the traffic is in both directions and two signal arms are employed, any 60 suitable arrangement would be employed whereby the operating rod of either signal arm would operate the shaft 2 independently of the other. A large variety of arrangements, depending upon the type of signal 65 employed, for accomplishing this result will

readily suggest themselves to those skilled in the art and I do not deem it necessary to illustrate the same.

From the description of the mechanism shown more particularly in Figs. 3 and 4 of the drawing, it will be seen also that the track instrument cannot be moved to safety and that the train will therefore be stopped if the home signal arm does not return to danger, because while the signal arm is in the clear position, the lever 3 is in its extreme position to the right of that shown in Fig. 2, and hence the notch 74 will be moved from under the lug 121 and the lever 21 will be prevented from falling and cannot 75 release the collar 6.

The circuit breakers 53, 54 and 65 are in the circuits of the relays A, B and D and if either of the track instruments should be at clear the corresponding circuit for 80 A, B or D is interrupted and the relay de-energized, and it will be understood that the signal clearing circuits (not shown) can be arranged to include contacts at these relays so that when the relays are deenergized the corresponding signals cannot clear. If 85 the track instrument therefor is inadvertently out of position the signals must remain at danger until it is repaired.

The signal arms have been described as 90 normally at danger, but as will also be obvious to those skilled in the art, these may be kept normally at safety, according as the system is normal safety or normal danger. Throughout the description, the track instrument has been described as adapted to 95 operate a valve to set the brakes on the passing train, but this track instrument may also be adapted to trip or set a signal indicating device on the train instead of operating the brake setting valve. Furthermore, 100 mechanical circuit breakers may be substituted for the relays a^1 , b^1 , c^1 and d^1 which 105 may be operated by the wheels of the train.

Many other changes besides those already 110 indicated may be made in the system of circuits and in the arrangement of the various elements and in the details of construction of the mechanism without departing from the spirit of my invention, and all 115 such changes and variations and modifications are contemplated as fall within the scope of the appended claims.

I claim:

1. In combination with a train stop located adjacent a railway track and having an operative and an inoperative position, a signal alongside the track, a shifting appliance electrically controlled and in part by said signal for operating the train stop and operable to throw the train stop to inoperative position only when the signal has been operated from clear to danger, substantially as specified.
2. In combination with a train stop lo-

cated adjacent a railway track and having operative and inoperative positions, a signal alongside the track adapted to indicate clear and danger, a shifting appliance for operating the train stop, and means preventing the shifting appliance from throwing the train stop to its inoperative position while the signal is at clear, substantially as specified.

3. In combination with a train stop located adjacent a railway track, and having operative and inoperative positions, a shifting appliance for said train stop having controlling magnets, circuits for energizing said magnets, a signal alongside the track 15 mechanically connected to the shifting appliance, and mechanical means for preventing the shifting appliance from throwing the train stop to inoperative position while the signal indicates clear, substantially as 20 specified.

4. In combination, a train stop, a signal located beside the track, signal circuits governing the movements of the signal, a controlling appliance for said train stop, said 25 appliance taking its initial power from the signal beside the track and having fluid controlling means for regulating the speed of its operation, and electric means for controlling the operation of said appliance, substantially as specified.

5. In combination: a train stop; a shifting appliance for said train stop; a signal, the signal being adapted to store energy in the shifting appliance; track circuits; signal 30 circuits having included therein contacts governed by relays in the track circuits and also a controlling magnet; and circuit breakers in the signal circuit operated in accordance with the indication of the signal, substantially as specified.

6. A shifting appliance of the character above described, deriving its power from the movement of the signal beside the track in combination with said signal, a fluid 45 governor for controlling the speed of action of the appliance, a holding magnet for holding the appliance in the clear position, a holding magnet for holding it in the danger position, and a lock which locks it in the danger position when the latter magnet fails for any reason.

7. A shifting appliance of the character described, deriving its power from the movement of the signal beside the track, in combination with said signal, a fluid governor 55 controlling the speed of action of the appliance, a holding magnet for holding the appliance in the danger position, and means for locking the appliance in the danger position when said magnet fails for any reason.

8. A shifting appliance of the character above described, deriving its power from the movement of the signal beside the track in combination with said signal, holding 65 magnets for controlling the movements of

said appliance the circuit of one of said magnets being controlled by track circuits and the circuit of the other being jointly controlled by track circuits and said signal, signal circuits jointly controlled by the track 70 circuits and the instrument operated by the shifting appliance, the circuits being so interlocked that the instrument and the signal cannot both be in the clear position at the same time.

9. The combination in a block signal system of a section or block of railway upon which the traffic is in both directions, a track instrument adapted to control trains in both directions on said section, a shifting appliance for setting the track instrument for trains in both directions, said shifting appliance having means for regulating its speed of operation, and electric means for controlling the shifting appliance.

10. The combination in a block signal system of a section or block of railway upon which the traffic is in both directions, a track instrument adapted to control trains in both directions on said section, a shifting appliance for setting the track instrument for trains in both directions, said shifting appliance having fluid controlling means for regulating the speed of its operation, and electric means for controlling the shifting 95 appliance.

11. The combination in a block signal system of a section or block of railway track upon which the traffic is in both directions, a track instrument for setting the brakes of the trains, a shifting appliance for positioning said instrument properly for approaching trains, electric means controlling the operation of the shifting appliance for trains in both directions, and means for regulating the speed of the operation of the shifting appliance.

12. The combination in a block signal system, of a section or block of railway upon which the traffic is in both directions, a track 110 instrument for setting the brakes of the train, a shifting appliance for positioning the track instrument properly for approaching trains in either direction, electric means controlling the operation of the shifting appliance for trains in both directions, means for regulating the speed of the operation of the shifting appliance and means for furnishing power for operating the signal and the shifting appliance.

13. The combination in a block signal system, of a block or section of railway track, a movable signal for such block having different positions indicating safety, danger and caution, a track instrument, for 115 setting the brakes of the train, a shifting appliance for shifting the track instrument and mechanically connected to the signal, and magnets and electric circuits controlling said appliance on the approach of trains 120 125 130

from either direction, substantially as specified.

14. The combination in a block signal system, of a section or block of railway upon which the traffic is in both directions, a movable signal for such block having different positions for indicating safety, danger and caution, a track instrument for setting the brakes of the trains, a shifting appliance for positioning the track instrument properly for approaching trains, electric means controlling said shifting appliance for trains in both directions, and means supplying power for the shifting appliance and the signal.

15. 15. In a system of the class described, in combination, a track instrument adapted to assume either an inoperative or an operative position and in the latter position to co-operate with a device on a passing train to automatically apply the brakes or operate a signal thereon, mechanism governing the position of the track instrument, a visual signal, connections between the visual signal and said mechanism, and means preventing the track instrument from assuming an inoperative position while the visual signal is at clear.

16. In a system of the class described, in combination, a track instrument adapted to assume either an inoperative or an operative position and in the latter position to co-operate with a device on a passing train to automatically apply the brakes or operate the signal thereon, mechanism for governing the position of the track instrument including track circuit controlled magnetic devices, a visual signal, connections from the latter to said mechanism and adapted to operate the same, and means preventing the track instrument from assuming an inoperative position while the visual signal is at clear.

17. In a system of the class described in combination, a track instrument adapted to assume either an inoperative or an operative position and in the latter position to co-operate with a device on a passing train to automatically apply the brakes or operate a signal thereon, mechanism for governing the position of the track instrument, visual signals, connections between the visual signals and said mechanism, and means for storing up energy in said mechanism to shift the track instrument to inoperative position when the visual signals are moved to clear, substantially as specified.

18. In a system of the class described for a single track having trains passing thereover in both directions, in combination, a track instrument adapted to assume either an inoperative or an operative position, and in the latter position to co-operate with a device on a passing train to automatically apply the brakes or operate a signal thereon upon trains going in either direction, mechanism governing the position of the track

instrument, a visual signal normally at danger, and means for storing energy in said mechanism upon the movement of the visual signal from danger to clear, said signal being movable from clear to danger independently of any movement of the track instrument or governing mechanism, substantially as specified.

19. In a system of the class described, in combination, a track instrument adapted to assume either an inoperative or an operative position and in the latter position to co-operate with a device on a passing train to automatically apply the brakes or operate a signal thereon, said track instrument being adapted to normally assume the operative position, mechanism adapted to shift the track instrument from the operative to the inoperative position, and including track circuit controlled magnetic devices, a visual signal and connections from the motor power of the signal to said mechanism and adapted to operate the same, and a signal circuit including a relay, said circuit having a circuit breaker therein operated by the track instrument.

20. In a system of the class described adapted for a single track having trains passing thereover in both directions, in combination, a track instrument adapted to assume either an inoperative or an operative position, and in the latter position to co-operate with a device on a passing train to automatically apply the brakes or operate a signal thereon, said track instrument being adapted to normally assume the operative position, mechanism for shifting the position of the track instrument from the operative to the inoperative position, said mechanism including track circuit controlled magnetic devices, visual signals for each direction of the train, a signal circuit for each of the signals, each of said signal circuits including a relay and having a circuit breaker therein operated by the track instrument.

21. In a system of the class described, in combination: a train stop having operative and inoperative positions and normally held in operative position; a visual signal; track circuits having relays therein; signal circuits, the latter having contacts therein governed by the relays of said track circuits, said signal circuits having also included therein a circuit breaker operated by the train stop and closed when the latter is in its operative position, substantially as specified.

22. In combination: a train stop having operative and inoperative positions and normally held in operative position; shifting mechanism for said train stop for moving the latter from operative to inoperative position; means for storing energy in said shifting mechanism; signals; and electri-

cially controlled means governing the movements of said shifting mechanism, said means including circuits having circuit breakers therein operated by the signals, substantially as specified.

23. A mechanism of the class described comprising a casing, a rod movable therein, a lever for moving said rod, a sleeve slidably mounted on the rod, a collar secured to the rod, and a spring disposed between the collar and sleeve, a pair of movably mounted members adapted to engage and prevent the movements of the collar and sleeve and to also assume a position out of the path of movement of the collar and sleeve, mechanism for operating each of said members, each of said mechanisms including a magnet armature, and a magnet coöperating with each of said armatures.

24. In a signal system of the class described a track instrument, mechanism for shifting the track instrument comprising a casing, a rod movable therein, a lever for moving said rod, a sleeve slidably mounted on the rod, a collar secured to the rod, and a spring disposed between the collar and sleeve, a pair of movably mounted members adapted to engage and prevent the movements of the collar and sleeve and to also assume a position out of the path of movement of the collar and sleeve, mechanism for operating each of said members, each of said mechanisms including a magnet armature, a magnet coöperating with each of said armatures, and track circuits for controlling the energizing of said magnets.

25. In a system of the class described, in combination, a track instrument, means for shifting the track instrument comprising a casing, a rod movable therein, a lever for moving said rod, a sleeve slidably mounted on the rod, a collar secured to the rod, and a spring disposed between the collar and sleeve, a pair of movably mounted members adapted to engage and prevent the movements of the collar and sleeve and to also assume a position out of the path of movement of the collar and sleeve, mechanism for operating each of said members, each of said mechanisms including a magnet armature, a magnet coöperating with each of said armatures, track circuits for controlling the energizing of one of said magnets and track and signal controlled circuits jointly controlling the energizing of the other of said magnets.

26. In a system of the class described, in combination, a track instrument adapted to assume either an inoperative or an operative position, and in the latter position to coöperate with a device on a passing train to automatically apply the brakes or operate a signal thereon, said instrument being normally in an operative position, mechanism for shifting said instrument to its inopera-

tive position, a visual signal, a signal circuit therefor having a circuit breaker included therein operated by the track instrument and closed when the track instrument is in operative position, and means for furnishing power to said mechanism operable when the signal is operated, said mechanism including a movable member, devices for controlling the movements of said member, magnets for controlling said devices, track circuits for one of said magnets and combined track and signal controlled circuits for the other of said magnets, said combined track and signal circuits having included therein circuit breakers operated by the visual signal.

27. In a system of the class described, in combination, a track instrument adapted to assume either an inoperative or an operative position and in the latter position to coöperate with a device on a passing train to automatically apply the brakes or operate a signal thereon, said instrument being normally in an operative position, mechanism for shifting said instrument to its inoperative position, a visual signal, a signal circuit therefor, and means for furnishing power to said mechanism operable when the signal is operated, said mechanism including a movable member, devices for controlling the movements of said member, magnets for controlling said devices, track circuits for one of said magnets and combined track and signal controlled circuits for the other of said magnets, said combined track and signal circuits having included therein circuit breakers operated by the visual signal.

28. In a system of the class described, in combination, a section of track divided into a plurality of insulated sub-sections, each of said sub-sections being provided with a track relay and battery, a track instrument adjacent the track and located opposite one of the insulations, a shifting appliance for the track instrument, a visual signal adapted to indicate danger, caution and safe, a signal circuit, and means for supplying power to the shifting appliance operable when the signal is operated, said shifting appliance including a movable member, devices for controlling the movements of said member, a pair of magnets for controlling said devices, track circuits for one of said magnets, circuits for the other of said magnets including circuit breakers adapted to be closed when the signal is changed from its normal to its extreme opposite condition and thereby complete circuits for energizing the second named magnet, each of said circuit breakers operated by the signals being opened when the signal returns to its normal position, thereby breaking the energizing circuits for the second named magnet, substantially as specified.

29. In a system of the class described, in

combination, a track instrument adapted to assume either an inoperative or an operative position, and in the latter position to cooperate with a device on a passing train to automatically apply the brakes or operate a signal thereon, said track instrument being normally in operative position, mechanism for shifting the track instrument from the operative to the inoperative position, means for supplying power to the shifting mechanism, and electrically controlled means including track circuits for governing the movements of said mechanism, and automatically operated locking means for preventing the shifting mechanism from moving the track instrument to a safety position in case of either the failure of the proper formation of the track circuits or the return of the signal to normal position as the train advances along the track.

30. In apparatus for train control, in combination: a train stop having operative and inoperative positions; a signal; shifting mechanism for the train stop; connections between the shifting mechanism and the signal; electrical means governing the operation of the shifting mechanism; and mechanical means for preventing movement of the train stop to inoperative position while the signal is at clear, substantially as specified.

31. In apparatus for train control, in combination: a train stop having operative and inoperative positions; a signal; shifting mechanism for said stop; connections between the signal and the shifting mechanism arranged to store energy in the shifting mechanism when the signal goes to clear, whereby the shifting mechanism may move the train stop from operative to inoperative position; an electrically controlled lock preventing the operation of the shifting mechanism while the signal is at clear; and mechanical means operated by the signal for preventing accidental release of said lock while the signal is at clear, substantially as specified.

32. A train stop shifting appliance including, in combination: a supporting frame; a slideable shaft; means for moving said shaft; an electrically controlled lock governing the movement of said shaft in one direction; and locking mechanism for preventing accidental release of said electrically controlled lock, substantially as specified.

33. In apparatus for train control, in combination: a train stop; a signal; a shifting appliance comprising a frame, a shaft slideable therein; a spring mounted on said shaft between a fixed and a slideable collar thereon,

an electrically controlled lock normally preventing the movement of the fixed collar in one direction, a second electrically controlled lock for preventing the movement of the slideable collar in an opposite direction, a mechanically operated locking mechanism for preventing accidental release of said first-named electrically controlled lock; connections between the train stop and the shaft of said shifting appliance; connections between the signal mechanism and the shifting appliance arranged to compress said spring when the signal goes to clear; and means for operating said mechanical locking mechanism operated by the signal, substantially as specified.

34. In apparatus for train control, in combination: a train stop having operative and inoperative positions and normally in operative position; a signal having clear, caution and danger positions; a shifting appliance connected to the train stop and to the signal and receiving its energy from the latter; track circuits having relays therein; a circuit having a magnet therein, said circuit having contacts therein governed by some of said track relays; two magnets governing the operation of said shifting appliance, one of said magnets being normally energized and the other being normally de-energized, the circuit for the normally energized magnet having contacts therein governed by the relay; and a patch circuit having included therein a circuit breaker closed when the signal indicates caution, for bridging the contacts in the normally energized magnet circuit which are controlled by the relay and adapted to delay the operation of the shifting appliance, substantially as specified.

35. In apparatus for train control, in combination: a train stop having operative and inoperative positions; a signal adapted to indicate clear, danger and caution; a shifting appliance connected to the train stop and to the signal and deriving its power from the latter; and electrically controlled means governing the operation of the shifting appliance, said means including circuits formed in accordance with the indication of the signal and arranged to release the shifting mechanism at one time when the signal indicates clear and at a later time when the signal indicates caution, substantially as specified.
